United States Patent Office

Des. 204,663
Patented May 10, 1966

204,663

DRAWER HANDLE

Morris Loeb, 697 West End Ave., New York, N.Y.

Filed Aug. 20, 1965, Ser. No. 86,658

Term of patent 14 years

(Cl. D10—8)

FIG. 1 is a top plan view of a drawer handle showing my new design.

FIG. 2 is a bottom plan view.

FIG. 3 is a side elevational view with the outer face of the handle facing downwardly.

FIG. 4 is a side elevational view with the outer face of the handle facing upwardly.

FIG. 5 is a perspective end view from the lefthand end of the handle.

FIG. 6 is a perspective end view from the righthand end of the handle.

I claim:

The ornamental design for a drawer handle, as shown.
